UNITED STATES PATENT OFFICE.

HUGER W. JOHNSTONE, OF IDLEWILD, GEORGIA.

CAR-COUPING.

SPECIFICATION forming part of Letters Patent No. 349,652, dated September 21, 1886.

Application filed December 10, 1885. Renewed August 24, 1886. Serial No. 211,768. (No model.)

To all whom it may concern:

Be it known that I, HUGER W. JOHNSTONE, of Idlewild, in the county of Gordon and State of Georgia, have invented a new and useful Improvement in Car-Couplings; and I do hereby declare that the following is a full, clear, and exact description of the same.

The invention set forth in this application is an improvement upon that form of car-coupling, now well known, in which a knuckle is pivoted in one arm of the draw-head, and forms, when locked in place, one part of the hook which couples the cars.

The main part of my invention concerns the locking-key, by which the knuckle is held in place when the cars are coupled.

My object is, first, to simplify this locking mechanism; secondly, to cause it to move for the purpose of locking the knuckle automatically and by gravity, thereby dispensing with springs; thirdly, to locate the locking-bolt on one side in the arm of the draw-head, so that it may be accessible either from the platform or from the ground outside of the track; fourthly, to increase the bearing-surface of the locking-key and guard against breakage from excessive strain; and, fifthly, to provide for locking the knuckles, by means of an ordinary pin, in case of loss or breaking of the key.

In the accompanying drawings, which show my invention, Figure 1 represents a plan view of the draw-head with the knuckles and lock, part of the upper plate being broken away. Fig. 2 shows a longitudinal section taken vertically through the draw-head on line *x x* of Fig.

1. Fig. 3 represents the knuckle detached.

In the drawings, A indicates the knuckle, which is, in the main, of ordinary construction. It is pivoted at 1, also in the ordinary manner, in the upper and lower plates, 2, of the arm E of the draw-head. It differs from the ordinary knuckle in the shape of the rear arm, which is curved on its rear face in the arc of a true circle, the curve being continuous with the front face of the knuckle, so that the knuckle in swinging to couple or uncouple will always be within the limits of the draw-head. A notch or recess, *e*, is cut through in the rear face from top to bottom, and this is so placed that when the knuckle is interlocked with its fellow on the opposite car the notch registers with a key in the arm of the draw-

head. This key *a* is of nearly triangular shape, narrowest on the rear, and slides freely on the bottom of an inclined slot made from front to rear, but slightly inclined inward at its forward end from the line of draft of the car. The incline of the bottom of the slot is from the rear forward, and forms the way on which the key slides forward automatically to engage with the notch in the knuckle. The front end of the key *a* is vertical, and the rear projects from the face of the draw-head for connection with any suitable operating device, though it is not absolutely essential that it project beyond the face of the head. The slot in which the key moves is made in the central casting, but is covered by the upper and lower plates, or by metal left on the upper and under sides, excepting that an opening is made in the upper and lower plates in line with the forward end of the key when in lock. In this position the lower forward corner of the key is in the lower hole, as shown in Fig. 2 at 5, and gives additional steadiness and strength to the lock. The upper hole is used only in event of the key being broken, when it may be utilized for dropping in a bolt, either round or square, and fitting the holes and the notch. The inner face of the draw-head is curved, and has a shoulder, *d*, against which the spur *c* of the knuckle strikes when the knuckle has reached the rear limit of its movement. This spur swings across the face in the slot 3, formed to allow its passage, and brings up when the slot in the knuckle registers with the key end.

On the end of the key *a*, I form a rabbet, *t*, to catch and lock the knuckle on a curve, and a corresponding shoulder is formed, over which the rabbeted part fits when the lock is fully inserted. As the key is in the arm of the draw-head and projects to the side, it is readily accessible, and I may attach levers, heretofore shown by me, or any suitable mechanism.

When this coupling is mounted on a car-frame such as that shown in my Letters Patent of the United States No. 307,955, the draw-head will "give and take" on curves, and will couple easily on curved or on straight track. The broad lock, in its slot and its lodgment in the hole in the under plate, gives a very broad and secure bearing and great strength.

Ordinary retaining mechanism connected with the lever may be used to hold the key to

the rear when it is desired not to couple. When the key is left free, the movement of the knuckles in coupling brings the curved rear face of the knuckle against the end of the key 5 and pushes it back, and as the key rests against the curved face of the knuckle during all its movements, the said key is always in readiness to lock as soon as it registers with the locking-notch. The upper and lower plates, 2 2, 10 and the knuckle have openings registering with each other, so that the ordinary pin and link may be used, and as the key rests against the knuckle or the curved face thereof during all movements, it is always in readiness to lock 15 as soon as it registers with the locking-notch.

I am aware that it is old in this class of car-couplings to provide pins and latches for locking the jaws in place adapted to act by gravity, and I do not broadly claim this.

20 I claim—

1. In a draw-head having a knuckle formed with a curved rear face continuous with the front curve of the knuckle and turning in a curved recess of the draw-head, an inclined 25 way formed in the draw-head, with a straight inclined bottom extending from its front opening to its rear opening in the upper surface of the draw-head, and a straight key adapted to bear by gravity against the curved face of the 30 knuckle and to lock the same, substantially as described.

2. The knuckle having a notch and rear curved face continuous with the front face, and spur *c*, in combination with the correspondingly-curved face of the draw-head, and the shoulder *d* at the inner extremity of the curved recess of the draw-head, all substantially as described.

3. The arm of the draw-head, having the inclined slot for the key, arranged approximately 40 in line with the draft, in combination with a straight key arranged in the slot, and having its rear end projecting to the rear and side and adapted to operate by gravity, in combination with the notched and curved knuckle, substantially 45 as described.

4. A knuckle of a draw-head having a rear curved face, with a vertically-arranged slot or notch in its curved face, in combination with a key set on edge, and of approximately triangular shape and sliding on an inclined way in the arm of the draw-head, the said way and key extending to the rear and side with a straight bottom, substantially as described.

In testimony whereof I have signed my name 55 to this specification in the presence of two subscribing witnesses.

HUGER W. JOHNSTONE.
